UNITED STATES PATENT OFFICE.

RUDOLF GAERTNER, OF MERKELSGRÜN, NEAR CARLSBAD, AUSTRIA-HUNGARY, ASSIGNOR TO KARLSBADER KAOLIN-INDUSTRIE-GESELLSCHAFT, OF MERKELSGRÜN, NEAR CARLSBAD, BOHEMIA, AUSTRIA-HUNGARY.

INSULATOR FOR HIGH-POTENTIAL CURRENTS.

SPECIFICATION forming part of Letters Patent No. 696,958, dated April 8, 1902.

Application filed January 13, 1902. Serial No. 89,605. (No model.)

To all whom it may concern:

Be it known that I, RUDOLF GAERTNER, a citizen of the Empire of Austria-Hungary, and a resident of Merkelsgrün, near Carlsbad, Bohemia, Austria-Hungary, have invented new and useful Improvements in Insulators for High-Potential Currents, of which the following is a specification.

This invention has for its object an improved insulator for high-potential currents.

In order to increase the insulating property of porcelain insulators, they have been made of several bells connected together by a layer of glaze, as is mentioned in American Patents Nos. 600,475 and 605,119. It is evident that bells which are to be connected together by the glaze must have a thick layer of glaze at their contact-place. As, however, the porcelain glaze has a different coefficient of expansion from the mass of the porcelain it cracks in thick layers—that is to say, after cooling it does not form a homogeneous glaze, but a mass traversed by innumerable fine cracks and pores. These cracks in thick layers of glaze increase under variations of temperature and are further considerably increased in insulators exposed to the atmosphere when a current of very high potential is conveyed over the insulators, whereby the latter are considerably heated. It is evident from the foregoing that thick layers of glaze by reason of their liability to crack do not increase the insulation, but rather diminish it, and thus layers of glaze in the interior of the insulator only fulfil the object when they cover the mass in the ordinary thin layer.

In order to avoid the above-mentioned drawback, by the present invention the separate bells are so connected with one another that an interstice is formed between them in such manner as to afford an air-jacket practically inclosing the inner bell, and thereby the num-

ber of the glazed walls and also the space between the cable and the support is increased.

The insulator shown in the accompanying drawing consists, for instance, of two bells *a b*, and has on its outer bell *a* a projecting edge *c*, which is fixed in a corresponding annular recess *d* in the bell *b* in a second heating by means of a layer of glaze, so that between the two bells *a* and *b* an interstice or air-jacket *e* is formed. As the separate bells are provided with an even thin layer of glaze on their outer and inner surfaces, an insulating layer is provided between the cable and the iron post or support, which is composed of the porcelain, four layers of glaze 1 2 3 4, and the interstice or air-jacket *e*. It is evident that by this method of increasing the relative distance apart of the cable and the iron support, by increasing the number of layers of glaze inside the insulator and interposing an air space or jacket, an insulation is produced which greatly exceeds that of all such insulators hitherto made.

Having now particularly described and ascertained the nature of my said invention and in what manner the same is to be performed, I declare that what I claim is—

1. A high-potential electric insulator composed of a plurality of bells connected together at the points *d* and *c* and having an air-space *e* practically inclosing the inner bell.

2. A high-potential electric insulator composed of a plurality of glazed bells glazed together at the shoulders *d* and *c*, and having an air space or interstice *e* between them.

In witness whereof I have hereunto set my hand in presence of two witnesses.

RUDOLF GAERTNER.
